UNITED STATES PATENT OFFICE

THOMAS J. CRAWFORD, OF YOUNGSTOWN, OHIO

POLE STRUCTURE

Application filed September 30, 1929. Serial No. 396,158.

This invention relates to hollow metal members and more particularly to tubular poles such as are used to support electric conductors, pipes, wires, cables and the like. 5 Heretofore, one form of metal pole, which has been used for this purpose has been made by inserting one end of a piece of pipe into the end of a larger piece, and then pressing the overlapping portions together with dies. 10 This necessitates the use of low carbon metal and hence requires an objectionable weight in order to obtain a pole of the desired strength. The method is also objectionable as the amount of metal, which had to be used, made 15 the cost excessive.

Another form of pole has been made from seamless tubing of different diameters with the end of one section reduced to form a neck into which the end of the adjacent section has 20 been pressed, but seamless tubing is objectionable because of the excessive cost. A more important consideration however, is the fact that the reduction in diameter increases the deflection, notwithstanding the fact that 25 the same fibre stress is maintained throughout.

It is well known that deflection in trolley wire supports causes breakage of insulators, particularly when a snow and ice load is added 30 to the wires. Hence, to avoid such deflection, it has been necessary to increase the wall thickness and thereby to add materially to the weight and cost of manufacture. Again, there is an overlapping of metal at 35 the joint which adds to the weight and reduces the efficiency. Still another form of pole which has heretofore been used, has been made from a tube which is drawn downwardly at predetermined intervals so as to maintain 40 the same wall thickness but varying the diameter. This pole is open to the same objection as to deflection, and is too expensive to manufacture.

The principal objects of the present invention therefore, are to make a pole which will require a minimum of material in order to obtain the necessary strength, and also to provide an economical method of manufacturing poles of any desired form.

50 I accomplish these objects by providing a

pole wherein the sections are butt welded end to end. One form of the invention comprises the utilization of blanks which are butt welded at the ends to form a composite blank, which is then formed to make a hollow member having a horizontally extending seam. 55 The welding of the longitudinal and transverse joints may be accomplished by the usual butt welding and pipe welding machines. Other forms of my invention are illustrated 60 in the drawings and are hereafter described, while the essential features are pointed out in the claims.

In the drawings, Fig. 1 is a plan view showing the stock used in one form of pole manufacture embodying my invention; Fig. 2 is a cross-sectional view of the material shown in Fig. 1; Fig. 3 is a plan view showing the blanks butt-welded together; Fig. 4 is a cross-sectional view of Fig. 3; Fig. 5 shows 65 the welded blanks formed into a tube; Fig. 6 is a cross-section taken along the line 6-6 in Fig. 5; Fig. 7 is a view of the welded pole; Fig. 8 is a cross-section taken along the line 70 8-8 of Fig. 7; and Figs. 9 and 10 are longitudinal cross-sectional views of modifications 75 of my invention.

Referring more particularly to the drawings in Figs. 1 and 2, the pieces of raw stock, which may be used in making a pole, are indicated by 21, 22 and 23. These pieces, as shown, are all of the same width so that they can be formed into a tube of uniform diameter, but they are of progressively decreasing thickness, the bottom section 21 being 85 heavier than the intermediate section 22, which in turn, is heavier than the top section 23. While I have shown three sections, it is obvious that two or any number greater than two sections could be used. The length, 90 thickness and number of sections are determined by individual design requirements.

The next step in the manufacture of the pole may be to weld the ends of the bottom, intermediate and top sections together, as at 95 24 and 25 (Figs. 3 and 4). These butt welds may be made by any convenient process such as electric resistance welding. The sections may be jointed together so as to produce a blank having one plane surface which forms 100

the outside of the tube or pole, the other surface being formed in a series of steps to allow for the variations in thickness of the sections.

- 5 The blank may then be hot or cold rolled or pressed into a cylindrical or tubular shape, as shown in Figs. 5 and 6, leaving an open seam 26. The edges of the seam may then be welded together as at 27 (Figs. 7 and 8) by 10 resistance, arc, gas or other welding process. The completed tube is then ready for any finishing operations which may be necessary, such as rolling or pressing the top portion 23 into a squared shape, in order to facilitate attachment of fittings of equipment. While only a square cross-section is described, an elliptical, polygonal or any other desired shape could be employed.

20 A pole similar to that shown may also be manufactured from sections of standard tubing. To this end, pieces having the proper uniform external diameter, and varying internal diameters may be welded together at their ends by any convenient method.

- 25 In Fig. 8, I show a pole having a uniform internal diameter and a varying external diameter. A pole of this type may be manufactured by forming the blank shown in Figs. 3 and 4 over a mandrel and into a tube having a uniform internal diameter. The longitudinal seam may then be welded by any convenient method, such as arc or gas welding, and the pole finished for fittings in any desired manner. A pole of this type may also 30 be manufactured by butt welding the ends of pieces of tubing of the desired dimensions.

In Fig. 10, I show a form of pole which may be easily and economically manufactured by welding sections of standard tubing 40 together at their ends. In the modification shown in Fig. 10, the averages of the internal and external diameters of the sections 30, 31 and 32 may be substantially equal, and the thickness of the walls may be progressively 45 varied. The sections may be butt-welded together as at 33 and 34.

It is to be understood that the upper section of poles made according to any of the 50 above modifications may be deformed in order to facilitate attachment of fittings. Furthermore, if desired, the entire pole may be deformed to obtain various ornamental shapes.

From the foregoing description of the preferred forms of my invention, it will be seen 55 that I have provided a pole which may be easily and economically manufactured, in which great strength is secured with a minimum of material and which may be adapted 60 to a variety of uses.

I claim:

1. A hollow metal one piece cantilever member comprising successive sections of different thickness, butt-welded together and 65 having internal and external dimensions, the

average of which lies between the external and internal dimensions of the section having the thickest walls.

2. A hollow metal one piece cantilever member, comprising successive sections of different thickness, butt-welded together and 70 having internal and external dimensions approaching in a series of steps toward some value greater than the internal and less than the external dimensions of the section having 75 the thickest walls.

In testimony whereof, I hereunto affix my signature.

THOMAS J. CRAWFORD.
